UNITED STATES PATENT OFFICE

HENRY G. MICHAELSON, OF ROCKFORD, ILLINOIS

SHOW CASE

Application filed July 7, 1928. Serial No. 290,912.

This invention relates to a showcase especially designed and adapted for the attractive displaying of fountain pens, pencils, desk sets, etc., although, of course, not particularly limited to such use.

The principal object of the present invention is to provide a showcase affording the maximum degree of visibility for articles placed on display therein, particularly articles of the kind referred to, the case being so constructed that everything in it can be seen easily when observed either from a distance or close up.

Another important object of my invention is to provide a showcase so designed as to utilize every available bit of otherwise wasted space for storage purposes to accommodate such surplus stock as a merchant is apt to carry on hand. Incidentally, the construction is such that all parts of the interior of the case are easily accessible for the placing and removal of articles as well as for the occasional cleaning of the case and stock therein.

The invention is fully described in the following specification in which reference is made to the accompanying drawing, wherein—

Figure 1 is a perspective view looking at the front of a showcase made in accordance with my invention, this view serving in a measure to demonstrate the high degree of visibility afforded; and

Fig. 2 is a central vertical transverse section.

The same reference numerals are applied to corresponding parts in the two views.

Showcases as heretofore constructed used in the merchandising of fountain pens or other merchandise have ordinarily included an upper tier of display trays, pads, etc., setting almost horizontally so that the merchandise could be seen to advantage only at very close range, that is to say, only when the customer stood directly in front of the showcase. Furthermore, these cases frequently had a lower compartment for the display of desk sets, combination pen and pencil sets, or other merchandise and it was only by stooping that the customer could see the same.

These objections are practically entirely obviated in accordance with the present invention by disposing the upper tier of trays, pads, or containers, hereinafter referred to as trays, at the rear of the case and at a more or less acute angle to the vertical, thereby exposing to view everything therebeneath which would otherwise be obscured so far as the customer standing directly in front of the case is concerned and also rendering everything visible to one standing at a distance. Moreover, by making a good part of the side walls of the case of glass the articles in the upper tier of trays, as well as those therebelow, are found to be seen to very good advantage from the sides as well as the front of the case. It will presently appear how this arrangement also lends itself to the provision of storage drawers, the presence of which is entirely unnoticeable from the customer's side of the case, and how all parts of the interior of the case are rendered extremely easily accessible to the clerk or merchant.

The showcase illustrated comprises a base 5 with or without legs 6 and, rising from the base, a wooden back frame 7 and segmental, substantially triangular, wooden side walls 8, the triangular form of the latter being departed from to the extent of increasing the slope of the upper portion of the front edges 9 of the side walls, as at 10. What is lacking in the wooden structure thus far described to complete a showcase of rectangular form is made up by plate glass side and front walls 11 and 12, respectively, and top 13. An upper tier of two rows of trays 14 for pens, or other merchandise, is supported on a slide 15 of hollow wooden construction having strips 16 fastened to the opposite side walls thereof received in guide-ways in the form of grooves (not shown) provided in the side walls 8. I also contemplate using extension slides instead of the strips 16, similar to those used on filing cabinet drawers. The slide 15 may, if desired, be equipped with a door 17 in the back wall thereof hinged at 18 and having any suitable form of catch 19 in order to make the space inside the slide available for storage purposes. Ordinarily, however, this will not be found necessary in 100

view of the ample storage space provided for in the other places as hereinafter described. A handle 20 is provided on the slide 15 to be grasped by the clerk or merchant in pulling the slide out or in pushing the same back into place. The slide moves freely back and forth over and in slightly spaced relation to a ledge 21 in the form of a board extending horizontally crosswise of the case and fastened at its ends to the side walls 8. I prefer to provide some suitable form of means for limiting at least the outward movement of the slide so that there will be no danger of the same being pulled out too far and the contents of the trays spilled. For this purpose I have illustrated at 22 a knob provided on a rod 23 received in a hole drilled into the ledge 21 and having a latch 24 on the inner end thereof. The latch 24 can be turned by means of the knob 22 to project from the ledge 21, as shown, or, on the other hand, may be turned to an out-of-the-way position. When projecting from the ledge the latch will engage a stop 25 on the slide 15 to limit outward movement and another stop 26 to limit inward movement. To permit removal of the slide it is only necessary to turn the knob 22 until the latch 24 allows the stop 25 to pass the same. It will, of course, be evident that when the slide is in its normal position the back thereof lies flush with the back frame 7 of the case and neatly closes the opening provided therefor in said frame. It is customary for the merchant to handle combination pen and pencil sets. These may be placed on a shelf 27 supported, as by means of brackets 28, on a cross-piece 29 depending from the front of the ledge 21. The space beneath the ledge 21 and behind the cross-piece 29 I prefer to utilize as storage space and have, therefore, shown a drawer 30 equipped with a handle 31 which is slidably received beneath the ledge above the cross-rail 32. This drawer is found to be a handy place to keep trays or boxes of pens. A lower tier of one row of display trays 34 for pens is supported on the inclined front 35 of a removable bolster 36. The inclination of the trays 34 may be, and preferably is, at a greater angle to the vertical than the trays 14 to make the same visible more in side elevation than would otherwise be the case. The top of the bolster 36 is used for the displaying of such larger articles as desk sets. These, by reason of the rearward disposition and the special inclination of the upper tier of trays 14, are rendered easily visible to the customer standing in front of the showcase, especially if not placed too near the rear of the case. It is not necessary for the customer to stoop to see what is in the lower part of the case; at the same time, everything is visible at an appreciable distance. A door 37 hinged, as at 38, affords ready access to the trays 34 and the top of the bolster 36 and

when fully opened also affords access to a storage compartment 39 provided under the bolster. A cross-piece 40 under the bolster cuts down the size of the compartment just enough to avoid the likelihood of articles being thrust too far forward under the bolster where they might be hard to reach. Smaller desk sets or boxes containing pens or combination sets of pencils and pens may be placed in the compartment 39. A large drawer 41 equipped with a handle 42 is preferably provided in the base 5 and will accommodate the larger sized desk sets and any additional stock not accommodated in either the drawer 30 or compartment 39.

The showcase, it will appear from the description, is one particularly well adapted to the requirements stated, and, moreover, displays the articles therein in such a way as to attract the attention of a passer-by. It is also believed to be evident that the cost of the construction has been kept to a minimum considering the various advantageous features that have been incorporated.

The appended claims have been drawn with a view to covering the present construction as well as any simulations thereof such as are bound to occur to those skilled in the art as a result of this disclosure.

I claim:

1. A showcase adapted for display of small articles, like fountain pens, and larger articles, like desk sets, comprising a frame having bottom and back walls of suitable opaque material and side walls suitably of the same material of acute triangular form, a lower display platform in said case between the base portions of the side walls adapted to receive the larger articles for display, an upper display platform for smaller articles disposed in said case between the top portions of the side walls and supported thereby above the lower platform over the rearward portion thereof, leaving enough space therebetween for the articles placed on the lower platform, there being a short front wall depending from the upper platform not far enough to interfere with a view of the articles on the lower platform from the front of the case, a storage drawer under said platform behind said wall and concealed thereby, a shelf mounted on and projecting forwardly from said wall not far enough to interfere with a view of the articles on the lower platform from in front of the case, glass top and front walls for said case and glass side walls for the case of acute triangular form fitting in between the front and top walls and the aforesaid opaque side walls.

2. A showcase adapted for display of small articles, like fountain pens, and larger articles, like desk sets, comprising a frame having bottom and back walls of suitable opaque material and side walls suitably of the same material of acute triangular form, a lower

display platform in said case between the base portions of the side walls adapted to receive the larger articles for display, an upper display platform for smaller articles disposed in said case between the top portions of the side walls and supported thereby above the lower platform over the rearward portion thereof, leaving enough space therebetween for the articles placed on the lower platform, glass top and front walls for said case and glass side walls for the case of acute triangular form fitting in between the front and top walls and the aforesaid opaque side walls.

15 In witness of the foregoing I affix my signature.

HENRY G. MICHAELSON.
